UNITED STATES PATENT OFFICE.

WILLIAM ALBERT HICKMAN, OF PICTOU, NOVA SCOTIA, CANADA.

BOAT AND BOAT PROPULSION.

1,044,176.

Specification of Letters Patent. Patented Nov. 12, 1912.

Application filed January 25, 1911. Serial No. 604,658

To all whom it may concern:

Be it known that I, WILLIAM ALBERT HICKMAN, a subject of the King of Great Britain, and resident of the city of Pictou, in the Province of Nova Scotia, in the Dominion of Canada, have invented certain new and useful Improvements in Boats and Boat Propulsion; and I do hereby declare that the following is a full, clear, and exact description of the same.

The invention relates to improvements in boats and boat propulsion, as described in the present specification and illustrated in the accompanying drawings that form part 15 of the same.

The invention consists essentially in the novel arrangement of the propelling means, whereby the parts of the mechanism incidental to inertia in respect to the driving power are clear of displacement resistance 20 with the water during rapidity of movement.

The objects of the invention are to eliminate displacement resistance entirely, particularly in high speed boats, to obtain more power from the installation of machinery 25 for propulsion than would otherwise be obtained from a corresponding weight of machinery, to increase the efficiency of the propeller blades, to trim the boat better by the 30 positioning of the engine plant and generally to provide an arrangement which will greatly simplify the construction of power boats and at the same time increase their efficiency.

35 In the drawings, Figure 1 is a side elevation of a boat at rest and the water line, showing the application of this invention to the hydroplane class of boats. Fig. 2 is a side elevation of a boat at speed and the 40 water line, showing the invention applied to the same class of boat. Fig. 3 is a perspective detail of the stern of a boat showing the shafts projecting therethrough and the propellers mounted on said shafts. Fig. 4 is a 45 plan view of the boat showing the arrangement of the engines, shafts and propellers. Fig. 5 is a longitudinal, sectional view of the stern portion of the boat showing a means for raising and lowering the propeller. Fig. 50 6 is a side elevation of the stern portion of the boat showing in section a means for raising and lowering the rudder. Fig. 7 is an enlarged perspective detail of the rack and portion of the propeller shaft. Fig. 8 is a

side elevation of a boat of the hydroplane 55 class showing a modification of the application of this invention. Fig. 9 is another hydroplane. Fig. 10 is a stern view of the same.

Like numerals of reference indicate corresponding parts in each figure.

The present invention is primarily concerned with the development of speed boats and it is well known that the hulls have been made so light and of such a shape that they 60 practically rise out of the water and slide along on the surface. In the construction of hydroplanes, this is particularly noticeable and the only friction remaining in regard to the hull is what is commonly termed "skin 65 friction," therefore, it is presumed that the minimum has been reached in respect to the hull, but there is another resistance with which designers have had great trouble due to the displacement of water by the propeller mechanism below the water line, such as the inner portion of the blades of the 70 wheel customarily used in screw propulsion, the hub, the shaft and the supporting bracket and struts. It does not matter how much 75 the weight of these parts may be reduced by constructing them of a very fine grade of material, they are still there and boats of very light construction of the hydroplane 80 type have been known to rise up out of the water on these very parts, thus showing what the resistance will accomplish, and taking this fact into consideration, the drag of 85 these parts in the water will be readily understood. The main problem, therefore, is 90 to do away with the displacement resistance offered by the shaft and other under water gear incident to screw propulsion and with this in view, the parts are arranged and a form of screw propeller is used to paddle or 95 scull the boat through the water in place of driving it by screw action.

Referring to the drawings, 1 is a motor boat here shown as of the hydroplane type having its step 2 intermediate of the length 100 of the hull. 3 and 4 are gasoline motors installed within said hull one at each side of the center line of the boat and preferably in parallel arrangement, said motors being set up substantially horizontal or in alignment with the bottom of the boat. 5 and 6 are shaft bearings astern of said motors.

7 and 8 are propeller shafts directly con-

nected to the motors 3 and 4 respectively and extending sternwardly therefrom through the shaft bearings 5 and 6 and out through the shaft orifices 9 and 10 in the stern of the boat, said shaft orifices being at or above the water line of the boat when at rest, or below.

11 and 12 are propellers mounted on the outwardly projecting ends of the propeller shafts 7 and 8 respectively and formed of right and left hand spiral blades 13 and 14 respectively extending from the hubs 15 and 16, said shafts being arranged to revolve in opposite directions.

15 It will now be seen that the boat is furnished with two preferably parallel shafts connected to two gasoline motors respectively and extending through the stern wall of the boat, said boat being formed to rise 20 on the water at speed and practically skim over said water, so that the volume of water at the stern is not materially decreased in regard to its density. The propeller wheels are preferably about mid-way submerged, 25 when the boat is at rest, so that when the motors speed up the stern will lift and leave only the paddle portions of the blades dipping into the water during rotation. The water thrown backward through the rotation of the paddles will be thrown in an oblique rearward direction in respect to the 30 keel of the boat, consequently there will be some lateral movement of the stern, which will have a tendency to swing the bow, but 35 this may be overcome by either movable planes or a rudder in the case of a single propeller, but with the two propellers working toward one another there will be no such swing of the hull.

40 In Fig. 5, an addition is made to the mechanism shown in Figs. 1 to 4, whereby the height of the shaft in relation to the speed water line may be adjusted.

45 17 is a rack sliding in the guide 18.

45 19 and 20 are lengths of hollow shafting jointed flexibly at 21, the length 20 extending through the bearings 5 or 6 and the length 19 extending through the shaft orifices 9 or 10, as the case may be and through 50 the looped strap 22 secured to the guide 18.

23 is a toothed plate rigid with the hollow section 19 and in constant engagement with the rack 17 toward the lower end thereof.

55 24 is a pinion coaxing with the rack 17.

25 is a shaft journaled in the bearings 26 and extending forwardly and having at the forward end a suitable hand wheel 27.

28 and 29 are sections of the propeller shaft flexibly joined at the joint of the hollow shafts 19 and 20.

30 is a propeller wheel mounted on the end of the shaft 28.

31 is a vertical slot through the stern wall 65 of the hull. 32 is a sliding cover to said

slot through which the hollow shaft 19 extends, said cover sliding into a recess 33.

34 is the rudder pivotally secured to the rudder plate 35 said rudder plate 35 being rigid with the screw box 36.

37 is a key rigid with the screw box 36. 70 38 is a bracket rigidly secured to the stern wall of the boat and formed at the rear end thereof with the key-way 39, in which said key 37 slides, and a bearing 40 at the upper 75 end thereof.

41 is a shaft carrying at its lower end the screw 42, which operates in the screw box 36, and at its upper end, the bevel gear wheel 43.

44 is a shaft journaled in the bearings 45 and extending forwardly and carrying at its aft end the bevel gear wheel 46 coaxing with the bevel gear wheel 43 and at its forward end the hand wheel 47.

80 This completes the detail description of the parts in this invention and it must be understood that all these parts may be constructed and arranged in various ways, though in any of such arrangements, the propelling member must only have its efficient working parts submerged on the boat 85 gaining its speed.

90 There are other forms of hulls to which this invention may be applied, such as some 95 of the most extraordinary hydroplanes in which in Fig. 9 it will be noticed that the shaft extends outwardly from the lift board 48 at speed in place of through the stern. Further the movable front and rear planes 100 may be used in some constructions as illustrated in Fig. 10 particularly for boats with only one propelling wheel, as the planes can be set to guide the boat accordingly, but 105 these are only possible modifications and generally speaking the construction will be as more particularly described herein, especially so in the most of these speed boats. The application of this means of propulsion to the more practical navigation of boats is not described herein, as it is obvious that it will be adopted for such purpose and in such manner as may be considered advisable, so long as the features set forth in the claims 110 for novelty are properly adhered to.

115 This description points out particularly that the hub, the shaft and the inefficient portions of the blades are all clear of the water at the speed level, therefore, it may be mentioned, particularly here that approximately two-thirds of each blade is submerged, being the full extent of the paddle portions of said blades and the blades, of which three on each wheel are shown as being the preferable number, in rotation reach 120 beyond the ends of the stern wall, that is to say, beyond the side walls at the stern thereof gripping the water where it is liable to be denser than it is directly at the stern, though as there is no screw action, there is 125 130

no racing of the wheel or inefficient stirring of the water.

What I claim as my invention is:

1. In boats and their propulsion, a sliding hull, a shaft bearing in the stern thereof contiguous to the water level in the rest position of said hull, a propeller shaft turning in said bearing, means for operating said shaft, and a propeller mounted at the rear 10 end of said shaft and during the period of speeding raising said hull and bearing and dipping only the working areas of its blades.

2. In boats and their propulsion, a journal bearing formed in the stern portion of 15 the boat above the bottom thereof, a propeller shaft journaled in said bearings and projecting therethrough above the speed water line of the boat, a propeller having a plurality of blades projecting from a central hub fixedly mounted on the integral 20 projecting end of said propeller shaft, each of said blades in its downward position engaging the water with its working area only below the lowest part of the hull and ex-

tending above the bottom, and means for 25 driving said shaft.

3. In boats and their propulsion, a pair of internal combustion engines, a pair of propeller shafts substantially parallel and operatively connected with said engines respectively at their fore ends, a pair of screw propellers fixedly secured on the aft ends of said propeller shafts and operated by said engines in opposite directions and a hull formed at the stern to receive said propeller shafts and support the same at a distance above the speed water level and the bottom of the boat, low enough to permit the blades to project below the bottom of the boat during rotation.

Signed at Pictou in the Province of Nova Scotia, in the Dominion of Canada, this tenth day of January, 1911.

WILLIAM ALBERT HICKMAN.
